United States Patent

Des. 241,867

Patented Oct. 12, 1976

241,867

SKI

Rudolf Ferch, Salzburg, Austria, assignor to Kastle
GmbH, Ried im Innkreis, Austria

Filed Jan. 9, 1975, Ser. No. 539,843

Claims priority, application Austria Nov. 19, 1974

Term of patent 14 years

Int. Cl. D21—02

U.S. Cl. D34—14 D

FIG. 1 is a top plan view of a ski showing my new design;

FIG. 2 is a side elevational view thereof;

FIG. 3 is a bottom plan view thereof;

FIG. 4 is a front elevational view thereof; and

FIG. 5 is a rear elevational view thereof.

The side of the ski opposite to that shown in FIG. 2 is identical.

I claim:

The ornamental design for a ski, substantially as shown and described.
